UNITED STATES PATENT OFFICE.

DONALD E. PRENVEILLE, OF OAKLAND, CALIFORNIA, ASSIGNOR OF ONE-HALF TO
ANTOINE E. M. PRENVEILLE, OF OAKLAND, CALIFORNIA.

BEAM COMPASS.

Application filed February 12, 1925. Serial No 8,658.

My invention relates to beam compasses having the beam thereof formed with adjustably related sections.

An object of the invention is to provide a device of the character described having the beam thereof provided with a handle portion for use in manipulating the device, and means associated with said handle portion for adjusting the relative positions of the compass points carried by the beam.

Another object of the invention is to provide a device of the character described having means associated with said adjusting means for holding the relatively movable portions in desired frictional engagement.

The invention possesses other objects and features of advantages, some of which, with the foregoing, will be set forth in the following description of the preferred form of my invention which is illustrated in the drawings accompanying and forming part of the specification. It is to be understood that I do not limit myself to the showing made by the said drawings and description, as I may adopt variations of the preferred form within the scope of my invention as set forth in the claims.

Referring to said drawings:—

Figure 1 is a plan view of the compass of my invention.

Figure 2 is a side view of the device, partly in section.

Figure 3 is a sectional view taken on the line 3—3 in Figure 2.

As illustrated in the drawings, the compass of my invention comprises a beam or rod 5, preferably formed in three sections 6, 7, and 8. As here shown the sections or arms 6 and 8 are provided at oppositely disposed extremities with sockets 11 and 12 respectively in which the various compass points are arranged to be removably and frictionally held, a pen 13 and needle-point carrying member 14 being here shown so held in the sockets 11 and 12 respectively. Formed in the section 7 of the beam are parallel guideways 16 and 17 in which the arms 6 and 8 are slidably mounted, while extending from said section transversely upward of the plane of movement of the sections 6 and 8 is an extension 18, here shown of cylindrical form and having the upper portion 19 thereof knurled to aid in holding the same.

Means are provided as part of the device for simultaneously moving the arms 6 and 8

through their guideways. As here shown such means comprises a pinion gear 21 mounted in the section 7 and arranged to operatively engage racks 22 and 23 provided on the arms 6 and 8 respectively, such racks 60 engaging said gear at opposite sides thereof. In this manner, it will be noted, rotation of the gear 21 will cause a corresponding simultaneous movement of the arms 6 and 8 with respect to the member 7 to thus cause 65 the sockets 11 and 12 to approach or separate as may be desired. Rotation of the gear 21 is here shown arranged to be effected by means of the rotation of a shaft or stem 24 which carries the gear and is mounted 70 in a bearing 26 extending axially through the extension 18. The end 27 of the shaft 24 preferably extends through and beyond the extension portion 19, and the exposed portion thereof is preferably knurled to 75 facilitate rotation by means of the fingers.

In order to maintain the compass points in desired relation during the use of the compass, means are provided which cooperate with the arm moving mechanism to hold 80 the relatively movable parts of the device in fixed relation. As here shown, the member 7 is provided with a slot 28 extending longitudinally therethrough between and parallel to the guideways 16 and 17 and extending into the extension 18 to a point substantially midway thereof. It will now be noted that the sections of the member 7 thus separated by the slot 28 may be pressed together, and that when so pressed they will 85 force the arms 6 and 8 against the opposite sides of the gear to thereby cause frictional engagement of the arms in their guideways. In order to effect such inward movement of the sections of member 7, the inner portion 90 95 31 of the handle 18 is preferably provided with threads 32 terminating at the small diameter of a conical surface 33 provided at the base of the extension 18. To cause the desired movement of the separated sections of the member 7, a lock-nut 34 is provided which is arranged to engage the threads 32 and has an inner edge portion 36 arranged to slidably engage the surface 33. In this manner, turning of the nut 100 105 34 on the threads 32 to advance the same toward the base of the handle will, through its engagement with the surface 33, force the portions of the section 7 together to provide any required frictional engagement of 110

110

the sections with each other, as hereinbefore described, so that relative movement of the sections may be hindered or entirely prevented as may be desired. It will be noted that the bearing 26 is enlarged at its lower end to prevent gripping of the shaft before the gear is gripped.

The stem portion 27, extension portion 19, and nut 34, it will now be noted, unite to provide a centrally disposed handle for the device which may be advantageously used in manipulating the same. Furthermore, with the compact arrangement here shown adjustment of the arms and locking or unlocking of the device may be readily accomplished while the compass is in use without necessitating the repositioning of the hand on the device or removing the pivot point from its position on the work. Then too, any wear of the gears or sliding bearings which may occur may be taken up by use of the locknut 34, so that wear does not impair the efficiency of the device.

In the event that it is desired to change the radius of the arc to be drawn about a given center, and at the same time keep the needle point set in its center, instead of using the shaft as the arm-adjusting means in the manner hereinbefore described, adjustment may be simply effected by loosening the locknut and directly moving the other arm to thereby set the sockets the required distance apart, it being noted that by reason of the gear, the arms and central member 7 will maintain their proper relation. Furthermore, it will be obvious that the arms may readily be replaced with longer or shorter ones, as desired, so that the device is adaptable for use for a wide range of work.

I claim:—

1. A beam-compass rod comprising a body member, an arm slidably mounted in said member, a manually rotatable shaft mounted in said member, a pinion mounted on said shaft, the arm having a rack operatively engaging said pinion, and means car-

ried by said member and adapted to cooperate therewith to press the arm and pinion into frictional engagement with various intensities. 50

2. A beam-compass rod comprising a longitudinally slotted body member having a guideway and a shaft bearing arranged therein, an arm mounted for movement in said guideway, a rotatable shaft mounted in said bearing, means operable upon the rotation of said shaft to move said arm through said guideway, and releasable means arranged to simultaneously and forcibly engage said arm between said first means and said member. 55

3. A beam-compass rod comprising a longitudinally slotted body member having parallel guideways and a shaft bearing provided therein, arms slidably engaging in said guideways, a shaft mounted in said bearing, a gear fixedly mounted on said shaft, there being racks provided on said arms and arranged to operatively engage 70 said pinion on opposite sides thereof, and manually operable releasable means cooperating with the body member to simultaneously cause the gripping of said gear between the arms and the frictional engagement of said arms the wall of their guideways. 75

4. A beam-compass rod comprising slidably engaged sections, an extension provided on one of said sections, manually controlled rotatable means carried by said extension and arranged to move the other section relative thereto, means on the section having said extension whereby the locking together of the sections may be effected, and manually controlled rotatable means mounted on said extension in concentric relation with said first means and operable in cooperation with said last means to lock said sections in fixed relation. 85 90

In testimony whereof, I have hereunto set my hand at Oakland, California, this 26th day of January, 1925.

DONALD E. PRENVEILLE.
